UNITED STATES PATENT OFFICE.

FREEBORN F. RAYMOND, 2d, OF NEWTON, MASSACHUSETTS, ASSIGNOR, BY MESNE ASSIGNMENTS, TO THE UNITED SHOE MACHINERY COMPANY, OF NEW JERSEY.

HEEL-ATTACHING MACHINE.

SPECIFICATION forming part of Letters Patent No. 651,447, dated June 12, 1900.

Application filed May 28, 1898. Serial No. 681,995. (No model.)

To all whom it may concern:

Be it known that I, FREEBORN F. RAYMOND, 2d, a citizen of the United States, residing at Newton, in the county of Middlesex and State 5 of Massachusetts, have invented a new and useful Improvement in Heel-Attaching Machines, of which the following is a full, clear, and exact description, reference being had to the accompanying drawings, forming a part 10 of this specification, in explaining its nature.

The invention is an improvement upon that described in my application for Letters Patent of the United States filed January 19, 1898, Serial No. 667,160. In said application I have 15 shown and described a nail and heel carrier and a top-lift carrier which are arranged to be rotated or turned upon a horizontal axis, but which do not reciprocate with the driving or spanking mechanism and which are fixed 20 in their relation to each other. In my present invention the nail and heel carrier and the top-lift carrier and spanker are rotated or oscillated upon a vertical arc, and the top-lift carrier and spanker is also made movable in 25 respect to the nail and heel carrier and is fed into operative position without moving the nail and heel carrier out of operative position, whereby it becomes possible to locate and hold it closely to the nail and heel carrier when 30 the latter is in operative position and to then also automatically or otherwise move it into operative position without moving the nail and heel carrier.

It further relates to means for automatically moving said top-lift carrier into operative position and for holding it out of operative position, also to means for oscillating or rotating the nail and heel carrier and the top-lift carrier and spanker simultaneously and 40 from operative or attaching positions to receiving positions and from receiving positions to operative or attaching positions, and which oscillating movement may be caused by the movement of the jack out of and into operative position or by movement of an independent lever or by the movement of the treadle in starting the machine.

In the drawings, Figure 1 is a view in front elevation of a machine having the features of 45 my invention. Fig. 2 is a view in vertical

section upon the line 2 2 of Fig. 1, showing the nail and heel holder and top-lift spanker and carrier in receiving positions and the jack removed from attaching position. Fig. 3 is a view upon the same section, enlarged, representing the center and upper parts of the machine only and the nail and heel carrier and top-lift carrier and spanker after they have been turned to operative position, the jack also being represented in operative position. 55 Fig. 4 is a view in vertical section, enlarged, upon the dotted line 4 4 of Fig. 1. Fig. 5 is a view in cross vertical section upon the dotted line 5 5 of Fig. 4. Fig. 6 is a view, partly in end elevation and partly in section, of the 60 nail and heel holder and carrier and top-lift carrier and spanker in their reversed or receiving position. Fig. 7 is a view representing the top-lift-centering device as provided with a handle by means of which it may be 65 readily opened for the reception of a top-lift. Fig. 8 is a detail view, in vertical section, taken through the nail and heel holder and top-lift carrier and spanker when in the position represented in Fig. 6. 70

The invention is applied to a machine having the organization of that described in my said application. The nail-drivers A and the last B and the nail and heel carrier C operate in relation to each other as therein described. The nail and heel carrier is adapted to receive nails loose or otherwise and heels in an inverted position and to transfer them from the inverted or receiving position to the attaching position. The last or work 85 support, with the unheeled shoe upon it, and the drivers are then movable in relation to the nail and heel carrier, the heel, and the attaching-nails as described in said application, and the heel compressed and attached 90 to the shoe.

The nail and heel carrier may have what is known as the "multiple-die" construction, in which event the driver-block a would carry multiple drivers to correspond. The nail 95 and heel carrier is mounted upon the frame C of the machine to be oscillated or turned, as described in said application. The top-lift carrier and spanker D is mounted upon the carrier C to be oscillated thereon and ro- 100

tated therewith. It is attached thereto in any desired way, and I have represented for this purpose the supports or rings d d' upon either side of the central section c of the nail 5 and heel carrier. These rings are preferably made thicker at the points d^2 , where they receive the top-lift carrier and spanker, in order that the top-lift carrier and spanker may be set away from the carrier a sufficient distance 10 to permit the closing movement of the carrier or spanker outside the nail and heel holder, or to the position represented in Figs. 4 and 5. The top-lift carrier and spanker comprises a plate d^3 , which is attached to these thickened 15 parts of the supports or wings and has a dovetailed recess d^4 in its outer surface; also, a sliding plate d^5 , having a dovetailed tongue d^6 to fit said dovetailed recess, and which is adjustable lengthwise the plate d^3 by means of 20 an adjusting-screw d^7 , carried by the ear d^8 of the plate d^5 and screwing into a threaded hole d^9 in the ear d^{10} of the plate d^3 . The outer surface of the plate d^5 forms the spanking-surface, and there is mounted upon this outer 25 surface the top-lift holding and centering devices, which are well shown in Fig. 1 and which comprise the two arms e e' , pivoted to the plate d^5 at e^2 e^3 , respectively, and geared together near the pivotal points by the sector-gears e^4 e^5 , so that the movement of one 30 arm causes the other arm to be moved the same extent, but in an opposite direction. Each arm also has a breast-gage e^6 , against which the breast of the top lift is held, and 35 ends e^7 , which bear against the edge of the top lift near its back end and serve to hold the breast of the top lift in contact with the breast-gages. Each arm also has the ear e^8 extending forward from the pivotal point, 40 and between which arms there is arranged a coiled compression-spring e^9 for closing the arms upon the top lift and holding them closed with a yielding pressure. This provides a very simple and effective top-lift 45 centering and holding device. It is attached to the plate d^5 to be movable with it lengthwise the plate d^3 for the purpose of longitudinally adjusting the position of the top lift in respect to the heel. The rings d d' 50 are arranged to turn upon the carrier C , so that the top-lift carrier and spanker may be movable on the carrier in respect to the nail and heel holder C . In its inoperative position the top-lift carrier and spanker is usually held latched back from the nail and heel holder and carrier, as represented in Figs. 1, 2, and 3, and against the pressure of the closing-spring E , which is contained in a cavity in one of the rings d d' , is curved to 55 the form of the carrier, has one end attached to or held stationary by it, and bears at its other end against the ring at the end of the recess. It is adapted to automatically move the top-lift spanker and carrier from the position represented in Fig. 3 to the position 60 represented in Fig. 4 upon the release of the latch F . The said latch is represented as

pivoted at f on the side of the part d^2 of the ring d and as having a latching end f' to engage a latching-shoulder f^2 on the carrier C . 70 It is held in engagement with said latching-shoulder by the spring f^3 . It is adapted to be moved down automatically to disengage the ring and the top-lift carrier from the heel-carrier and to permit the automatic movement to the top-lift carrier into operative position by means of the push-rod f^4 , which is adapted to engage the extension f^5 of the latch F . This push-rod is movable upward and downward in any desired way, and in 75 the drawings I have shown its lower end f^6 as connected with a cam f^7 on the shaft f^8 , which is constructed to impart to the rod vertical movements at the desired intervals.

The latch may be moved to disengage the 85 top-lift carrier upon the first upward movement of the jack, in which event the top-lift carrier and spanker will not be immediately movable under the nail and heel holder, as it will be prevented from so moving until the 90 heel on the heel-holder has been attached and the heeled shoe and last have moved downward sufficiently to remove the heel from the front edge of the top-lift carrier and then permit of its interposition between the heel-holder and attached heel. (See Fig. 4.) The nail and heel holder is adapted to receive loose nails or a loaded heel-blank. The receiving position of the nail and heel holder and of the top-lift carrier and spanker may 100 be in any position removed from over the last or work-support best adapted for the purpose. It will be understood, of course, that after the attachment of the heel-blank and top lift the top-lift spanker and carrier is 105 moved back to permit the latch F to engage and hold it and to also uncover the nail and heel holder in order that the nails and heel may be placed therein and thereon or a loaded heel placed upon it. It is preferable 110 that this be done after the heel-carrier and the top-lift carrier have been moved together to receiving position.

I have shown for turning the nail and heel holder and the top-lift carrier and spanker a 115 mechanism comprising a segment-gear H on the carrier C and a sector-gear h at the upper end of the arm h' , pivoted at h^2 . The sector h meshes with the gear, and upon an inward movement of the sector h the nail and heel holder and top-lift carrier and spanker are turned from their highest to their lowest position, (see Figs. 2 and 3,) and upon the reverse movement of the sector they are turned backward from their lowest to their highest 125 position. This sector h may have at each end a handle by which either the operator or his assistant may turn the nail and heel holder and top-lift carrier and spanker, or the sector-arm h' may be connected with a slide or hinged jack, so that the movement of the jack from its inoperative position in front of the attaching devices to a position in line therewith will also cause the nail and heel 130

holder and the top-lift carrier and spanker to be moved from inoperative position to a position to bring the heel in line with the jack. In Figs. 2 and 3 I have represented a horizontally-sliding jack K connected with said arm by a link h^3 , the arm having an extension h^4 below its pivotal point to which the link is secured. It will be observed that the connection is such that the inward movement of the jack causes the sector h to be moved and the nail and heel holder and the top-lift spanker and carrier to be turned downward by it and that the outward movement of the jack causes a reverse movement of the nail and heel holder and the top-lift carrier and spanker.

I prefer to first place the top lift in the top-lift holder while it is over the heel-holder and to then move the top-lift holder forward to compress its actuating-spring and engage its retaining-latch and then place the nails and heel. (See Fig. 2.) Any suitable jack may be employed, and it may be provided with vertical movement by any desired mechanism. In the drawings, as above stated, I have represented a sliding jack. This jack is movable upon the bed k in suitable ways. It has the spindle k' , which is vertically adjustable by means of the nut k^2 , and the spindle and nut are movable vertically when the jack is in operative position by the pressure-head k^3 , which is moved upward by the cam k^4 on the shaft f^3 . This cam is constructed to move the pressure-head, and thereby the last or work-support carried by the spindle k' , to the two levels necessary, first, for the compression and attachment of the heel, and, second, for the spanking of the top lift. The first of these movements is imparted by the cam-section k^5 and the second by the cam-section k^6 . A cam-roll may be interposed between the pressure-head k^3 and the cam. The shaft f^8 is represented as geared by gearing $k^7 k^8$ with a shaft k^9 , the outer end of which shaft k^9 carries crank-pins k^{10} , which are connected with the head k^{11} , to which the nail-drivers are attached and which extends through the cavity of the heel-carrier by means of connecting-rods k^{12} . (See Fig. 1.) The shaft k^9 may also be geared to a power-shaft k^{13} , upon which there may be a balance-wheel and also a clutch for starting and stopping the machine. I do not, however, confine myself to these specific devices for imparting vertical movements to the last or work-support. The heel-carrier is also provided with a hole M, opposite the perforated section, which when the perforated section is in its highest position will be below the drivers and in line with them, and an accidental starting of the machine can then cause no harm, as the drivers will reciprocate through this hole, where otherwise they would come into contact with the inner surface of the carrier.

While the perforated part of the heel-carrier is represented as integral with the remainder, I would say that this is done simply for the purpose of convenience; but in practice

said part would be made removable from the rest of the device.

In use the nail and heel holder in its receiving position is supplied with loose nails and a heel or with a loaded heel, and a top lift is placed in the top-lift-holding device of the top-lift carrier and spanker. The nail and heel holder and top-lift carrier and spanker are then moved either by hand or by the act of moving the jack into operative position, and the heel and its attaching-nails are brought into line with the last on the jack, and the top-lift spanker and carrier, with the top lift, is also brought to a position immediately behind the nail and heel holder. (See Fig.

3.) The machine is then started. The jack is moved upward, forcing the last and the shoe thereon into contact with the heel and the heel holder slightly in advance of the driving of the nails and maintaining that forcible contact during the driving of the nails. The jack, shoe, and attached heel are then moved downward, or away from the nail and heel holder, and the top-lift spanker and carrier is moved, preferably automatically, by the spring, as above described, to a position beneath the nail and heel holder and over the attached heel. The jack, shoe, and attached heel are again moved upward and the top lift spanked upon the heel and the jack and completed heel moved downward to their lowest position. The jack is then moved forward and by such movement, and if it is connected with the nail and heel holder the said nail and heel holder and the top-lift carrier and spanker are turned backward together to their receiving position; otherwise they are turned back together by hand, and the helper moves the top-lift carrier and spanker from over the nail and heel holder until it is automatically engaged and restrained by its latch.

It will be seen that the nail and heel holder remains in its attaching position during the attachment of the top lift. This insures a quicker feeding of the top lift than where the heel-holder is moved out of operative position to make room for the top-lift spanker and carrier, as in my said application, as it permits a relatively-light top-lift spanker and carrier to be brought into such close relation to it that it may be easily and quickly moved into operative position as soon as the heel is attached. It will also be seen that the nail and heel holder and top-lift spanker and carrier are moved back together to receiving position and there separated to expose the nail and heel holder and to bring both the nail and heel holder and the top-lift spanker and carrier into such position that both may be readily supplied with nails and a heel and with a top lift before the machine is started, which assists in the quicker operation thereof.

In Fig. 7 I have represented one of the arms of the top-lift holder as provided with the extension X, which forms or provides a handle by means of which the two arms may

be opened and held opened by hand as a preliminary to the placing of the top lift between the arms when they are permitted to close by the release of the handle to center the top lift in the holder.

5 Having thus fully described my invention, I claim and desire to secure by Letters Patent of the United States—

1. In a heel-nailing machine the combination of a nail and heel carrier, comprising a 10 perforated plate, and a support for said plate which is movable into and out of operative relation with the last or work-support, and with the drivers, and which support is also 15 provided with a safety hole or aperture which is adapted to be brought into the line of movement of the drivers when the nail and heel carrier is in its stationary and receiving position with the vertically-movable last or 20 work-support, and with the vertically-movable drivers, as and for the purposes described.

2. In a heel-nailing machine the combination of a nail and heel carrier movable upon a vertical arc from its receiving position to a 25 position between the drivers and the last or work-support, the said drivers and the said last or work-support, and an independent top-lift carrier and spanker also movable upon a vertical arc, and adapted to be interposed between the nail and heel carrier and the last or work-support after the attachment of the heel.

3. In a heel-attaching machine the combination of a nail and heel holder and carrier 35 movable upon a vertical arc from receiving to operating position, a top-lift carrier and spanker movable with the nail and heel holder and carrier and also independently movable in relation thereto, whereby they may both 40 be moved together from receiving position, and whereby also the top-lift carrier and spanker after the attachment of the heel may by a short movement be immediately moved into operative position without moving 45 the nail and heel holder and carrier.

4. In a heel-nailing machine a nail and heel holder and carrier movable upon a vertical arc and a top-lift carrier and spanker also movable upon a vertical arc and located 50 closely to the nail and heel holder, whereby they both occupy a receiving position at the same time, as and for the purposes described.

5. The combination in a heel-nailing machine of a gang of nail-drivers, means for reciprocating them vertically, a last or work-support, means for reciprocating it upon the line of reciprocation of the drivers, and a top-lift carrier and spanker movable upon a vertical arc with respect to the nail-drivers and 60 the last or work-support into and out of operative position between them.

6. In a heel-nailing machine the combination of a nail and heel holder and carrier movable upon a vertical arc, a top-lift carrier and spanker, means for closing it over the 65 exposed face of the nail and heel holder and

carrier, and devices for preventing said closing of the said top-lift carrier and spanker.

7. The combination in a heel-nailing machine of a nail and heel holder and carrier 70 movable upon a vertical arc, a top-lift carrier and spanker movable upon a vertical arc, an automatic device for moving the top-lift spanker and carrier to a position in line with the nail and heel holder and carrier and between it and the jack, the said jack as and for the purposes described.

8. The combination in a heel-nailing machine of a nail and heel holder and carrier movable upon a vertical arc from a receiving 80 to operative position, a top-lift carrier and spanker movable upon a vertical arc from a receiving to operative position, automatic means for moving said top-lift carrier and spanker to a position in line with said nail 85 and heel holder and carrier when in operative position, and means for holding said top-lift holder and carrier away from said nail and heel holder, as and for the purposes described.

9. The combination in a heel-nailing machine of a nail and heel holder and carrier 90 movable upon a vertical arc from a receiving to an attaching position, a top-lift carrier and spanker movable from a receiving to an attaching position independently of the movement of the nail and heel holder and carrier and adapted to be brought into line with the said nail and heel holder and carrier, and upon the same side of the center of the arc upon which they are both movable.

10. The combination in a heel-nailing machine of a nail and heel holder and carrier movable upon a vertical arc from a receiving to an attaching position, a top-lift carrier and spanker automatically movable from a receiving position to an attaching position beneath the nail and heel holder and top-lift spanker, and carrier holding and releasing mechanism for holding the carrier and spanker removed from the nail and heel holder and 105 for permitting its movement beneath the same after the attachment of the heel.

11. In a heel-nailing machine the combination of a nail and heel holder movable upon a vertical arc from a receiving to an attaching position, a top-lift carrier and spanker movable from a receiving to an attaching position beneath the nail and heel holder and carrier, a spring for so moving said top-lift carrier and spanker and a latch for holding 115 the top-lift carrier and spanker against the pressure of the spring, as and for the purposes described.

12. In a heel-nailing machine the combination of a nail and heel holder movable upon a vertical arc from a receiving to an attaching position, a top-lift carrier and spanker movable from a receiving to an attaching position beneath the nail and heel holder and carrier, a spring for so moving said top-lift carrier and spanker and an automatic latch-release operative during the attachment of 125 130

the heel to release the top-lift carrier and spanker and permit it to be moved against the heel and upon the removal of the heel from the heel-holder to also permit the top-lift carrier and spanker to be automatically moved into attaching position beneath the heel and nail holder and carrier.

13. The combination of a nail and heel holder and carrier adapted to be oscillated or turned upon a vertical arc from a receiving to an attaching position but to be non-movable vertically during the attaching operation, with a top-lift carrier and spanker movable with said nail and heel holder and carrier from receiving position and also independently movable of said nail and heel holder and carrier but non-movable when in attaching position, the nail-driving devices, the last or work-support and means for moving it vertically during the heel-attaching and top-lift spanking operations.

14. The combination in a heel-nailing machine of the nail and heel carrier and holder, supports for the top-lift carrier and spanker vertically movable thereon, having the outwardly-extending sections d^2 with a cross-plate supported by said sections, an adjustable spanker-plate carried upon the outer side of said cross-plate and top-lift centering devices mounted upon said adjustable plate.

15. The combination of the nail and heel holder and carrier supported by the frame of the machine and movable upon a vertical arc, a support for a top-lift carrier and spanker mounted upon said nail and heel holder and carrier to be movable thereon, a top-lift spanker and carrier carried by said movable support, a means to bear against said top-lift carrier and spanker to move the same, and a latch to hold the top-lift carrier and spanker away from the nail and heel holder and carrier and in opposition to the stress of the means for moving said top-lift carrier and spanker.

16. In a heel-attaching machine the combination of a vertically-reversible nail and heel holder and carrier, a last or work-support movable into and out of operative position, and devices connecting the jack with the reversible nail and heel holder and carrier whereby it is movable from a receiving to an attaching position and vice versa by the movement of the jack into and out of operative position.

17. The combination in a heel-attaching machine of a vertically-reversible nail and heel holder and carrier, a gear mounted thereon, a movable last or work-support and an

intermediate sector connected with the last or work-support and meshing with said gear.

18. In a heel-attaching machine the combination of a vertically-reversible nail and heel holder and carrier, a vertically-reversible top-lift carrier and spanker, a jack movable into and out of operative position connected with said carriers to reverse the same upon its movements, as and for the purposes described.

19. The combination in a heel-attaching machine of a vertically-reversible nail and heel holder and carrier, and a vertically-reversible top-lift carrier and spanker, also movable relatively with respect to the nail and heel holder and carrier, a horizontally and vertically movable jack means for connecting said jack with said nail and heel holder and carrier and adapted to be actuated upon the movement of the jack into and out of operative position to cause the nail and heel holder and carrier to be moved from receiving to attaching position and vice versa, as and for the purpose set forth.

20. In a heel-attaching machine a vertically-reversible nail and heel holder and carrier and a vertically-reversible top-lift carrier and spanker adapted to be reversible together, and the said top-lift carrier and spanker also having an additional movement relative to the nail and heel holder and carrier.

21. In a heel-attaching machine a vertically-reversible nail and heel holder and carrier, a vertically-reversible top-lift carrier and spanker reversible simultaneously with the nail and heel holder and carrier and also movable relatively thereto, the said nail and heel holder and said top-lift carrier being stationary in operative position with a reciprocating gang of drivers, and a jack movable vertically toward and from the heel-holder and from the top-lift carrier and spanker, as and for the purposes set forth.

22. The combination in a heel-attaching machine of a vertically-reversible nail and heel holder and carrier, a vertically-reversible top-lift carrier and spanker, the top-lift carrier and spanker being also movable relatively to the nail and heel-holder and carrier, a jack, and means for compressing the heel between the jack and heel-holder in advance of the driving of the attaching-nails and for spanking the top-lift and nail-driving devices.

FREEBORN F. RAYMOND, 2d.
